UNITED STATES PATENT OFFICE.

ARTHUR REGINALD ANGUS, OF SYDNEY, NEW SOUTH WALES, AUSTRALIA.

DEVICE FOR PREVENTING COLLISIONS BETWEEN RAILWAY-TRAINS.

1,190,617.

Specification of Letters Patent. Patented July 11, 1916.

Application filed April 17, 1909. Serial No. 490,552.

To all whom it may concern:

Be it known that I, ARTHUR REGINALD ANGUS, a subject of the King of Great Britain, residing at Barry street, Neutral Bay, Sydney, in the State of New South Wales and Commonwealth of Australia, solicitor, have invented new and useful Improvements in and Relating to Devices for Preventing Collisions Between Railway-10 Trains, of which the following is a specification.

The invention relates to an arrangement for protecting trains against following and meeting trains in which the running 15 train automatically raises members before and behind it by electrical means, and restores them to their normal position on leaving the corresponding portion of the track. The raised members serve for actuating 20 braking or signaling devices arranged on the train. On the train there are arranged three contact plates, of which one coöperates with fixed track members and places a source of current arranged on the train into connection with the electrical operating devices 25 of the movable track members, while the second and third contact plates bring into action a source of current arranged on the train which serves for operating the braking 30 or signaling devices on the passing over of the movable members raised by a following or meeting train or by the train itself.

The invention is illustrated by the accompanying drawings, which represent an example of train-protecting apparatus according thereto, and consists in the constructions and combinations of parts hereinafter described and particularly defined in the claims hereof.

40 Figure 1 shows the arrangement of the several track members and the apparatus on the locomotive. Fig. 2 is a diagram illustrating the course of the current between the track and the locomotive. Fig. 3 shows a fixed track member. Fig. 4 shows a movable track member and electric motors serving for raising and lowering and for locking the same. Fig. 5 shows the field magnet system of such an electric motor, particularly with reference to the locking and unlocking of the movable track member, the field magnet system used for raising and lowering being similarly constituted. Fig. 6, 45 which is composed of Figs. 6^A, 6^B, and 6^C, 50 shows the connection of the fixed members

with the operating devices of the movable members.

In Fig. 6 A and G indicate the beginning and the end of the track located between two main stations, while B, C, D, E 60 and F represent intermediate points, generally signaling stations, halting stations, and so on, which form the ends of successive sections of the track. Between the rails there are provided for the direction of running from A toward G fixed main members 65 21 and fixed supplementary members 27, and for the direction of running from G toward A corresponding main members 021 and supplementary members 027, which serve as 70 track circuit closers and are shown individually in Fig. 3. All the members 21 and 27 are at the same distance from the left hand line of rails while the members 021 and 027 are at the same distance from the right hand 75 line of rails. Moreover, between the rails there are located the movable main members 28 and 70 and the movable supplementary members 69 for the running direction A—G and the corresponding movable main members 80 028, 070 and supplementary members 069 for the running direction G—A. The distance of the members 28, 70 and 69 from the left hand line of rails is equal to that of the members 028, 070 and 069 from the 85 right hand line of rails and somewhat greater than the distance of the fixed members from the corresponding rails. The movable members 28 protect the running train in front, while the members 70 serve 90 for protecting it behind. The supplementary members 69 give a supplementary protection in front.

Each fixed member is of the construction shown in Fig. 3. On the insulated base plate 22, which is preferably fastened to a sleeper 20, there is located a standard 23 to which are pivoted two arms 24 which carry on their upper ends rollers 26. Between the fixed standard 23 and the arms 24 there are arranged springs 25 which, when the locomotive passes over the corresponding member, press the rollers against the side webs of a U-shaped contact plate 82 fastened to the locomotive. The plate 82 is, as shown in Fig. 3, provided with inclined ends 83 in order to produce a gradual deflection of the rollers.

Each of the movable members (Fig. 4) 95 consists of a base plate 29, which supports 100

an electric motor 30 having an armature 45. On the end 31 of the armature shaft there is keyed a bar 32. To this there is pivoted a pair of arms 33, with rollers 35, which are pressed against the webs of the corresponding contact plate of the locomotive. The base plate 29 can be fastened to special sleepers or to those of the track. Above the motor 30 there is a second motor 36 the 5 armature of which carries on one side of its shaft 37 a bar 38 which serves for locking the bar 32 in the vertical position.

10 The locomotive carries a battery 80, which may be charged by a dynamo driven from an axle of the locomotive. The positive 15 conducting wire 81 (Fig. 2) is connected with the said contact plate 82 and the negative pole is connected to earth through the framework of the locomotive.

20 The plate 82 coöperating with the fixed track members is insulated from the framework of the locomotive and is fastened thereto in such a manner that when the locomotive is running backward it can be 25 easily removed and placed on the right hand side. This is necessary, because the plate would otherwise, in the case of the running direction A—G, act upon the fixed contacts 021 corresponding to the opposite direction 30 of running.

Besides the plate 82 there are fastened to each locomotive and insulated therefrom two contact plates 85 and 86 of U-shaped cross section, which coöperate with the two 35 rows of movable track members 28, 70, 69, and 028, 070, 069 and are connected by means of a conductor 87 and one coil 89 of an electro-magnet with one pole of a second battery 88 arranged on the locomotive. The 40 second pole of the battery 88, which is charged by a dynamo similarly to the battery 80, is connected by means of a conductor 91 with an electric motor 92 and then, by means of a conductor 97 and the second 45 coil 98 of the electromagnet, with the framework of the locomotive and consequently with the earth. As soon as the electromagnet 89, 98 is energized its armature 100 closes, by bridging the contacts 90 and 99, 50 the circuit of the battery and the electromotor 92, so that it remains closed after the earth connection by means of the corresponding movable track member, is broken. The armature 100 is normally maintained out of 55 contact with the contacts 90 and 99 by means of a spring and it can be moved out of contact therewith by the locomotive driver by hand by means of the lever 101 (Fig. 1). The armature of the motor 92 carries a radial arm 93, which, by means of suitable 60 wires, is connected with the whistle 94, the brake 95, and the steam throttle 96.

The lowering of a raised member takes place in the following manner:—As the locomotive (Fig. 1) passes over a fixed rod 21

placed on the railway track (Fig. 6) in the block section C—D a short distance from the station D the plate 82 (Fig. 2) placed underneath the locomotive makes contact with part of the fixed rod 21 (Fig. 6)—that is 70 to say, the plate 82 (Fig. 2) underneath the locomotive comes into contact with the rollers 26 of the said fixed rod 21, and tends to press toward one another the pair of radial arms 24 (Fig. 3) of the said fixed rod 21, 75 the springs 25 between the vertical arm 23 of the said fixed rod and the radial arms 24 tending to maintain the pressure of the rollers 26 on the said plate 82—and the current from the accumulator 80 then passes along 80 the rollers 26 down the radial arms 24 along the base 22 (which is well insulated from earth contact) and thence along a wire 104 which leads from the base of the said last mentioned fixed rod 21 (the position of this 85 wire is indicated in Fig. 3) and connects the said fixed rod 21 with the rotating rod 28 placed not far distant from the station D; the current is conveyed by the wire 104 to the field magnets of the last mentioned 90 rotating rod 28. The path of the current after passing along the last mentioned wire may be followed on referring to Figs. 4 and 5; the current passes by way of the wire 104 to the terminal 54, thence by a wire 56 95 (Fig. 5) through field magnets 57 and by a shunt wire 58 through the armature 45, and returns by a wire 59 connected with the terminal 55 (Fig. 4) and thence by a wire to one of the track rails, thence by the wheels 100 and the frame of the locomotive to one terminal of the accumulator 80, the energization of the pair of magnets 57 causing the armature 45 to rotate in an anti-clockwise or a positive direction so as to raise the radial rod 38 affixed to the axle 37 of the rotating armature relating to the motor 36 clear of the radial rod 32 and radial arms 33 until the radial rod 38 is in a vertical position and presses against the contacts 60, 110 which may be held in position by a spring. The radial rod 38 bridges the contacts 60 and the current then flows from the wire 104 by way of a shunt wire through the bridged contacts 60. Each of the contacts 60 being 115 insulated from the motor 36, the current then flows along the wire 61 connected to one of the contacts 60 to the terminal 62 on motor 30, thence through a pair of field magnets such as 57 (Fig. 5) and the rotating armature of the motor 30 and returns through terminal 63 and thence by wire 64 back to a rail, thence by the locomotive's wheels and frame to one terminal of the 120 accumulator 80, the energization of the field magnets such as 57 causing the armature of the motor 30 to rotate clockwise—that is to say, in a negative direction—and thereby to lower the radial rod 32, with its radial arm 33, of the said rotating rod 28 until 130

the same rests in a horizontal position upon the stop 65 and further rotation in a negative direction is thus restrained by the stop 65. It should be explained that the armatures and magnets relating to both said motors 30 and 36 as shown in Fig. 4 are similar in construction and operation as shown in Fig. 5—that is to say, both motors 30 and 36 are intended as required to rotate 5 their armatures either in a positive or in a negative direction; the motor 30 and the motor 36 have similar sets of magnets 57 to rotate their respective armatures in a particular direction and sets of magnets 42 10 to rotate the armatures in the opposite direction; and the arrangement of connections shown in Fig. 5 applies to both motors 30 and 36.

Simultaneously with the lowering of the 20 member located immediately in front of the locomotive there is raised in the following manner a member 28 located at a greater distance in front of the locomotive:—The current flows as above described to the wire 25 104, then over the wire 105 to the terminal 40 of the motor 30, through the wire 43, through one pair of field magnets 42, and simultaneously by means of the wire 44 and the armature 45 to the conductor 39 30 and to the terminal 41 and from the latter to the track and to the other pole of the battery. The motor raises the bar 32, which in its vertical position bridges the contacts 46. The current flows now from the wire 35 105 over the contacts 46, the wire 48, to the terminal 49, and through the motor 36, and returns over the terminal 50, the wire 51, the wire 39, the terminal 41, and, by means 40 of a wire which leads to a rail, to the other pole of the battery. Since the current through the motor 36 passes through the other pair of magnets, the bar 38 is lowered 45 into a horizontal position, in which it locks the movable member. The spring 47 serves for holding the arm 32 in the raised position until it is locked.

When the locomotive passes over a raised member the following circuit is closed by means of the plate 85 or 86 (Fig. 2) from 50 the battery 88 to the magnet 89, the contact 90, the wire 87 to one of the plates 85 or 86, through the rollers 35, the arms 33 (Fig. 4) the bar 32, the spring 47, to the base plate 29, from there by means of a wire to a 55 rail of the track and by means of the wheels and the framework of the locomotive to the contact 99 (Fig. 2) through the magnet 98, the wire 97, the field magnets and the armature of the motor 92, and by means of the 60 wire 91 back to the battery 88. The motor rotates and by means of arm 93 blows the whistle 94, applies the brake 95, and actuates the throttle valve 96 to shut off steam.

When the current flows through the magnets 65 89 and 98 (Fig. 2) these are energized

and attract the common armature 100, which bridges the contacts 90 and 99. By these means a permanent circuit is closed from the battery 88 through the motor 92, notwithstanding that the contact between 70 the locomotive plate 85 or 86 and the corresponding member was broken immediately after the passing over of the locomotive.

In the same way as the members 28, the other movable members are raised and lowered. 75

The connection of the movable members with the fixed members is as follows:—Each of the fixed main members 21 (with the exception of the members located at the ends 80 of the track) is connected with four movable main members 28, 70. Thus, for example, the member 21 at C is connected with the movable member 28 at C, the movable member 28 at D, the member 70 between B and C, and the member 70 between A and B and the connection is such that when 21C is being passed over the members 70 between A and B and 28 at C are lowered and the members 70 between 90 B and C and 28 at D are raised. Each of the movable main members 28 or 70 is connected with two fixed main members—for example, the member 28 at D is connected with the member 21 at D and with the member 21 at C, the connection being such that the member 28 at D is raised when the member 21 at C is being passed over, and is lowered when the member 21 at D is being passed over. The distance apart of the two 100 nearest movable main members raised ahead of any two approaching locomotives (say the movable main member 28D for the running direction A—G and the movable main member 028C for the running direction 105 G—A) (Fig. 6) should be sufficient to permit two approaching trains, say number one traveling in the direction A—G and number two traveling in the direction G—A, whose locomotives' steam has been shut off and 110 brakes applied on passing over those movable main members 28 and 028 respectively to be pulled up or stopped before running a sufficient distance to permit a collision between the said approaching number one 115 train, which by assumption has passed over the said movable main member 28, and the other approaching train number two, which has passed over said movable main member 028. The distance apart of the said members 28 and 028 should be fixed to meet conditions such as the weight of the heaviest 120 train and brake power thereof, the grade of the railway track, and the greatest speed permitted on the particular part of the railway track on which the train is at the time traveling. In a similar manner the distance apart of, say, the movable main member 28E from the movable main member 028D 125 should be determined, and so on throughout 130

all the railway tracks protected by these improvements.

In certain circumstances the described safety arrangement in which there is always only one raised movable member in front of and behind the train might prove insufficient. In order to take these special circumstances into account the supplementary members 27 and 69 are arranged. The construction thereof is the same as that of the main members. The action, is, however, somewhat different. Thus, as is shown in Fig. 6, the fixed supplementary member 27 at C is connected with the movable supplementary members 69 at D and E in such a manner that when 27C is being passed over, 69D is lowered and 69E simultaneously raised. The supplementary member 27C is in front of the main member 21C in the direction of travel by a small distance, which is somewhat greater than the length of the contact plates carried by the locomotive. When the point C is being passed over consequently first the main member 28C is lowered and the main member 28D raised and then the supplementary member 69D lowered and the supplementary member 69E raised. The train is consequently at any time, after coming under the full protection of the system, protected forwardly by two movable members. If necessary, supplementary members can be arranged which similarly protect the train rearwardly.

The operation of the invention as it affects approaching trains and following trains on any part of the same protected railway track as illustrated in Fig. 6 is as follows: When one train traveling in the direction A—G has arrived at C and has passed over the fixed main member 21C and also the fixed supplementary member 27, it has raised in manner hereinbefore mentioned the movable main member 28D and also the movable supplementary main member 69E ahead of the locomotive and has also raised the movable main member 70 situate between B and C (it has also lowered the movable main member 70 between A and B) so that number three train traveling in the direction G—A will thus be prevented from approaching number one train by two movable members ahead of number one train and a following train, say number two, will be prevented from running into said number one train ahead of number two train by only one movable member which is located only one section behind number one train. It will thus be seen that while trains traveling in opposite directions are protected to the extent of two movable members as is desirable, a train is protected from a following train by only one section which is sufficient for the purpose and consequently only one section is blocked behind the train and not two and therefore traffic is not un-

necessarily delayed. Again as number three train traveling in the direction G—A arrives at E and passes over the fixed main member 021E and fixed supplementary member 027E it raises behind the locomotive the movable main member 070 situate between E and F and also raises the movable main member 028D and the movable supplementary member 069C and thus the oncoming train number one is prevented from approaching train number three, and also train, say number four, following behind train number three is prevented from running into train number three in manner hereinbefore indicated—that is to say, upon contact by any locomotive's plate 85 or 86 with any movable member the locomotive is stopped in the manner hereinbefore mentioned.

The distance apart of each movable member raised behind the position of a locomotive from its relative fixed member (as an illustration take the movable member 70 situate between B and C (Fig. 6),) and its relative fixed member 21C should be determined by conditions such as weight of train, brake power thereof, grade of railway track, and greatest speed permissible, all such possible conditions being considered and as far as practicable provided for.

It is to be remarked that the invention is intended to be employed chiefly outside the range of the points of the main stations. The connection of the members at the ends of the main track must be altered accordingly. It is further noted that if the arrangement for raising or lowering the members should not operate correctly the train is brought to rest automatically.

If the trains are always run only in the same direction on the track the arrangement can be correspondingly simplified.

The movable members 28, 69, 70, 028, 069, 070 shown in Fig. 6 have signals indicating their position and numbered 66, 67, 71, 066, 067, 071 respectively. These signals 66, 67, 71, 066, 067, 071 may be placed if desired at any suitable distance ahead of the particular rotatable members to which they relate so as to give a driver of a locomotive timely warning of the position of the rotatable members to which they relate. These signals are operated by railway employees as customary according to the positions of trains, but should a signalman fail to raise a signal when required to guide the driver, a corresponding train would be stopped by the use of these improvements as hereinbefore mentioned and as shown in the drawings herewith.

Various parts in connection with the invention may be arranged otherwise in sundry ways, duplicated, multiplied, varied or omitted without departing from the scope of this invention as indicated or claimed

herein: for example, if brakes only are to be applied the connections to the steam throttle may be omitted; again in place of an earth or rail return for a circuit a special 5 metallic return may be used.

Having now described the invention, what is claimed as new is—

1. In a railway signaling system and in combination, danger indicating means, signal transmitting means, and controlling means, all carried by a train, and in each 10 block section both signaling devices located on the track and all adapted when operative to come into contact with said signal transmitting means and thereby to operate said danger indicating means, and also controlling means located on the track and adapted to come into contact with the first mentioned controlling means and to be thereby caused 15 to render operative two of said signaling devices in front of said train and one of said signaling devices in the rear of said train and to render inoperative those of said signaling devices adapted to be similarly rendered operative by said train on contact with said controlling means located on the track in the next preceding block section.

2. In a railway signaling system and in combination, danger indicating means, signal transmitting means, and controlling means, all carried by a train, and in each 20 block section signaling devices located on the track and all adapted when operative to come into contact with said signal transmitting means and thereby to operate said danger indicating means, and also a first controlling contacting device located on the track and adapted to come into contact with said controlling means and to be thereby caused to render operative the nearer one of two of said signaling devices in front of said train and one of said signaling devices in the rear of said train and to render inoperative those of said signaling devices 25 adapted to be similarly rendered operative by said train on contact with said first controlling contacting device located on the track in the next preceding block section, and a second controlling contacting device located on the track and adapted to come into contact with said controlling means and to be thereby caused to render operative the further one of said two signaling devices and to render inoperative the one of said signaling devices adapted to be similarly rendered operative by said train on contact with said second controlling contacting device located on the track in the next preceding block section.

3. In a railway signaling system and in combination, danger indicating means, signal transmitting means, and controlling means, all carried by a train, and in each 30 block section both signaling devices located on the track and all adapted when operative

to come into contact with said signal transmitting means and thereby to operate said danger indicating means, electrical means for operating said signaling devices, and also, electrically connected with said electrical means, controlling means located on the track and adapted to come into contact with the first mentioned controlling means and to be thereby caused to complete electrical circuit connections through said electrical means and thereby to render operative two of said signaling devices in front of said train and one of said signaling devices in the rear of said train and to render inoperative those of said signaling devices adapted to be similarly rendered operative by said train on contact with said controlling means located on the track in the next preceding block section.

4. In a railway signaling system and in combination, danger indicating means, signal transmitting means, and controlling means, all carried by a train, and in each block section signaling devices located on the track and all adapted when operative to come into contact with said signal transmitting means and thereby to operate said danger indicating means, electrical means for operating said signaling devices, and also, electrically connected with said electrical means, a first controlling contacting device located on the track and adapted to come into contact with said controlling means and to be thereby caused to complete electrical circuit connections through corresponding ones of said electrical means and thus to render operative the nearer one of two of said signaling devices in front of said train and one of said signaling devices in the rear of said train and to render inoperative those of said signaling devices adapted to be similarly rendered operative by said train on contact with said first controlling contacting device located on the track in the next preceding block section, and a second controlling contacting device located on the track and adapted to come into contact with said controlling means and to be thereby caused to complete electrical circuit connections through other corresponding ones of said electrical means and thus to render operative the further one of said two signaling devices and to render inoperative the one of said signaling devices adapted to be similarly rendered operative by said train on contact with said second controlling contacting device located on the track in the next preceding block section.

5. A railway contacting device comprising two elements adapted to be moved transversely of the track in opposite directions and spring means adapted to tend to restore said elements to normal position during such movement.

6. A railway rotatable track contact de-

vice comprising a motor, an arm adapted to be turned thereby into operative position (wherein it is adapted to actuate signaling means on a train in contact therewith), a second motor, and a detent adapted to be turned by said second motor to maintain said arm in operative position.

7. A railway rotatable track contact device comprising a motor, an arm adapted to be turned thereby into operative position (wherein it is adapted to actuate signaling means on a train in contact therewith) and inoperative position, a second motor, a detent adapted to be turned by said second motor to maintain said arm in operative position, and means adapted when said arm is liberated by said detent to cause current to pass through the motor first above mentioned so as to effect the moving of said arm into inoperative position.

8. A railway rotatable track device comprising a motor, an arm adapted to be turned thereby into operative position (wherein it is adapted to actuate signaling means on a train in contact therewith) and inoperative position, a second motor, a detent carried by said second motor and adapted to be turned to maintain said arm in operative position, and means adapted on the movement of said arm into operative position to cause current to flow through the said second motor and to effect the movement of said detent into the position wherein it maintains said arm in the operative position.

9. A railway rotatable track device comprising a motor, an arm adapted to be turned thereby into operative position (wherein it is adapted to actuate signaling means on a train in contact therewith), a second motor, a detent carried by said second motor and adapted to be turned to lock said arm in operative position, and spring means adapted to maintain said arm in op-

erative position before the locking of said arm by said detent.

10. A railway rotatable track device comprising a rotatable arm and a rotatable detent adapted to lock said arm in operative position (wherein it is adapted to actuate signaling means on a train in contact therewith), separate motors adapted to control said arm and said detent and means adapted to be caused by the turning of said detent from the locking position to cause current to flow through the motor of said arm so as to move said arm into inoperative position, and also to be caused by the moving of said arm into operative position to cause current to flow through the motor controlling said detent so as to effect the movement of said detent into the locking position.

11. A railway rotatable track device comprising a rotatable arm, a rotatable detent adapted to be turned to lock said arm in operative position (wherein it is adapted to actuate signaling means on a train in contact therewith), motors connected to said arm and said detent respectively, each of said motors having two sets of windings adapted to cause rotation in opposite directions, and means adapted to be caused by the turning of said detent from the locking position to cause current to flow through the motor of said arm so as to move said arm into inoperative position, and also to be caused by the moving of said arm into operative position to cause current to flow through the motor controlling said detent so as to effect the movement of said detent into the locking position.

In testimony whereof I have signed my name to this specification in the presence of two subscribing witnesses.

ARTHUR REGINALD ANGUS.
